SHIFTABLE ATTACHMENT FOR SHIRT COLLAR TABS

Fernando Romero-Garrido, Guatemala City,
Guatemala

Application February 12, 1951, Serial No. 210,465

2 Claims. (Cl. 2—132)

1

This invention relates to wearing apparel and has to do more particularly, with shirts, the primary object being to provide a releasable hold-down device for the tabs of the collar of the shirt, so formed as to permit freedom of movement of the tabs with respect to the shirt when the latter is worn.

It is the most important object of the present invention to provide a shirt collar tab hold-down device taking the form of a fastening element 10 provided with a pair of releasable sections, one of the sections being secured to the shirt either rigidly or releasably, and the other section having connection with a small plate that is shiftably secured to the tab of the collar so that the tab can move freely with respect to the shirt as the wearer moves his head, neck, shoulders, and otherwise changes positions.

An important object of the present invention is the provision of a hold-down means as above set forth, wherein the shiftable plate is secured to the tab of the collar by means of an elongated strip secured to the tab and presenting a cavity within which the plate is free to reciprocate.

A further object of this invention is the provision of hold-down means that includes a shiftable plate upon which is mounted one of the parts of a fastening element, the plate being triangular-shaped and the cavity within which the same is disposed being complementally formed so as to limit the extent of movement of the plate in one direction with respect to the tab.

Other objects include details of construction, all of which will be made clear as the following specification progresses, reference being had to the accompanying drawing, wherein:

Figure 1 is a perspective view of a shiftable attachment for shirt collar tabs, made pursuant to my present invention.

Fig. 2 is an elevational view of that portion 40 of the device affixed to the collar tab.

Fig. 3 is a fragmentary, cross-sectional view taken on line III—III of Fig. 2.

Fig. 4 is an enlarged, detailed, cross-sectional view taken on line IV—IV of Fig. 3.

Fig. 5 is an enlarged, detailed, cross-sectional view taken on line V—V of Fig. 1; and

Fig. 6 is a sectional view similar to Fig. 5 illustrating a slight modification of the present invention.

Various attempts have previously been made to provide a satisfactory means to hold the tab of a shirt collar in a desired position and particularly against curling upwardly away from the shirt front. For the most part, such devices have

2

all been unsatisfactory for several reasons including bulkiness, unattractiveness and more important, the disadvantage resulting from the confinement that is presented when the tab is held against movement relative to the shirt. In other words, in the provision of a rigid interconnection, movement of the body of the wearer is impeded with resultant discomfort because, as the collar moves, the shirt must likewise move therewith.

As will hereinafter appear, the device of the present invention eliminates all of these difficulties and is additionally inexpensive and easily applied or formed for mounting on the shirt collar tab at the time of manufacture thereof.

A conventional shirt is illustrated in Fig. 1 of the drawing and broadly designated by the numeral 10. Shirt 10 obviously includes a front panel 12 and a collar 14 that terminates in a pair of tabs 16 normally designed to overlie the front panel 12 of the shirt 10.

While tabs 16 vary in particular configuration and shape in differing types of shirt collars, for the most part the same are at least substantially triangular-shaped as illustrated and include a pair of edges 18 and 20 that converge into a point or corner 22.

The hold-down device of the present invention is designed to be mounted in part on the lowermost face of the tab 16, or between the tab and the shirt front 12, and on the latter. A suitable fastening device is needed to carry out the objects of the invention and in this respect, there has been chosen for illustration, a conventional snap fastener that includes a section 24 and a section 26 secured to shirt front 12 and to a small triangular-shaped plate 28 respectively. It is of course, understood that a hold-down device of this kind is provided for each tab 16 respectively and accordingly, only one is illustrated and need be described.

The fastening element 24—26 includes a small spherical pin 30 on the section 26 that is received by an opening 32 in the section 24 and the interconnection is by frictional grip through the inherent resiliency of the material from which section 24 is formed.

The flat, triangular-shaped plate 28 rests directly against the lowermost face of the tab 16 for reciprocable movement toward and away from the tip or corner 22 through the medium of an elongated strip 34 that traverses the tab 16 and is secured directly thereto in spaced-relationship to the corner 22. The strip 34 may be made of any suitable material such as fabric and is secured to the tab 16 by lines of stitching 36 form-

ing a part of the collar 14. There is thus presented a cavity 38 between the strip 34 and the lowermost proximal face of the tab 16 for slidably receiving the triangular-shaped plate 28 in its reciprocable movement toward and away from the tip 22.

It is noted that the lines of stitching 36 also converge as the tip 22 is approached, and accordingly, the plate 28 is provided with opposed angularly displaced edges 40 complementary with the relative angularity between the lines of stitching 36.

It is clear therefore, that the extent of movement of the plate 28 toward the tip 22 is defined by the lines of stitching 36. Since the section 26 of the fastening element extends laterally from the plate 28 in a direction away from the tab 16 and because of the disposition of the fastening section 26 between the strip 34 and the tip 22, the extent of movement of the plate 28 away from the tip 22, is determined by the fastening element 26 striking the strip 34. The fastening element 26 however, does not prevent removal of the plate 28 and the element 26 thereon entirely from the tab 16 since the width of the cavity 38 may be increased when such removal is desired because of the flexibility of the material from which collar 14 is made and from which the strip 34 is produced.

Figure 3 of the drawing, illustrates the way in which the fastening element 26 is rigidly secured to the plate 28 at one corner thereof and Figure 5 illustrates in one embodiment of the present invention, the way in which the fastening element section 24 may be releasably secured to the shirt front 12. To this end, section 24 is provided with an externally threaded pin 42 that passes through a hole pierced in the shirt front 12 and receives a flat nut 44 on the innermost face of the shirt front 12.

It is clear that fastening elements other than that specifically chosen for illustration herein, and indicated by the numerals 24 and 26, may be provided within the principles of the present invention, and further, that means other than threaded pin 42 and nut 44, may be used to releasably secure one part of the fastening element to the shirt front 12. In any event, by virtue of such releasability, not only of the element 24 from the shirt front 12, but because of the fact that plate 28 and its element 26 may be easily removed from the tab 16, the shirt is quickly and easily placed in condition for laundering, starching and ironing. Accordingly, when the hold-down device is made as depicted in Figs. 1 to 5 inclusive of the drawing, a single set may serve any number of shirts and be used with the shirt that is being worn by the user while other shirts likewise equipped with strips 34, are being laundered. In the event however, that it is believed unnecessary to facilitate finishing the shirt by removal of the element 24, the same may be formed as illustrated in Fig. 6 of the drawing and designated by the numeral 50.

As is well known, element 50 corresponding

5 with the fastening section 24, may be purchased upon the open market and is adapted for clamping in place on shirt front 52, either manually or with ease and speed by use of machines manufactured for such purpose.

It is seen from the foregoing that when the hold-down device is placed in use and as the wearer of the shirt 10 moves his body in such manner as to likewise cause movement of the collar 14, the tabs 16 are free to yield to such movement irrespective of the fact that the same are secured to the shirt front 12. Such movement is provided for through the sliding or reciprocable movement of the plate 28 toward and away from the tip 22 relative to the tab 16.

Various other modifications may be provided for within the broad concepts of this invention and manifestly, those that come within the scope of the appended claims, are contemplated hereby.

Having thus described the invention what is claimed as new and desired to be secured by Letters Patent is:

1. In a shirt having a collar provided with a substantially triangular-shaped flap having a pair of edges converging into a free corner normally overlying the shirt front, a hold-down device for said flap comprising a strap between the shirt and the flap and secured to the latter between said edges; a flap-stiffening plate disposed 25 between the flap and said strap for sliding movement on the flap and the strap toward and away from said corner; and a fastener interconnecting the plate and the shirt, said fastener having releasably joined parts.
2. In a shirt having a collar provided with a substantially triangular-shaped flap having a pair of edges converging into a free corner normally overlying the shirt front, a hold-down device for said flap comprising a strap between the 30 shirt and the flap and secured to the latter between said edges; a plate shiftably disposed between the flap and said strap for movement toward and away from said corner; and a fastener having interconnected parts on the plate and on the shirt respectively, said plate having a pair of edges converging as said corner is approached, said strap having a pair of lines of securement to the flap, said lines converging as the corner is approached whereby to limit the extent of 35 movement of the plate toward the corner.
3. In a shirt having a collar provided with a substantially triangular-shaped flap having a pair of edges converging into a free corner normally overlying the shirt front, a hold-down device for said flap comprising a strap between the shirt and the flap and secured to the latter between said edges; a plate shiftably disposed between the flap and said strap for movement toward and away from said corner; and a fastener having interconnected parts on the plate and on the shirt respectively, said plate having a pair of edges converging as said corner is approached, said strap having a pair of lines of securement to the flap, said lines converging as the corner is approached whereby to limit the extent of 40 movement of the plate toward the corner.
4. In a shirt having a collar provided with a substantially triangular-shaped flap having a pair of edges converging into a free corner normally overlying the shirt front, a hold-down device for said flap comprising a strap between the shirt and the flap and secured to the latter between said edges; a plate shiftably disposed between the flap and said strap for movement toward and away from said corner; and a fastener having interconnected parts on the plate and on the shirt respectively, said plate having a pair of edges converging as said corner is approached, said strap having a pair of lines of securement to the flap, said lines converging as the corner is approached whereby to limit the extent of 45 movement of the plate toward the corner.
5. In a shirt having a collar provided with a substantially triangular-shaped flap having a pair of edges converging into a free corner normally overlying the shirt front, a hold-down device for said flap comprising a strap between the shirt and the flap and secured to the latter between said edges; a plate shiftably disposed between the flap and said strap for movement toward and away from said corner; and a fastener having interconnected parts on the plate and on the shirt respectively, said plate having a pair of edges converging as said corner is approached, said strap having a pair of lines of securement to the flap, said lines converging as the corner is approached whereby to limit the extent of 50 movement of the plate toward the corner.

FERNANDO ROMERO GARRIDO.
